UNITED STATES PATENT OFFICE

JOSEPH E. JOHNSON, OF ROSLINDALE, MASSACHUSETTS

WINDOW SCREEN

Application filed April 15, 1930. Serial No. 444,407.

This invention aims to provide an improved window screen having means for expediting and simplifying the putting on and taking off of the screen.

In the accompanying drawings, wherein I have shown merely for illustrative purposes one embodiment of the invention:

Fig. 1 is an inside elevation of a window casing with a half screen embodying this invention shown slidably attached thereto;

Fig. 2 is a transverse section through the screen shown in Fig. 1 taken on the line 2—2 of said figure;

Fig. 3 is an inside elevation of a window casing showing a full length screen embodying this invention and attached to said casing; and

Fig. 4 is a detail section taken on the line 4—4 of Fig. 3.

In the particular embodiment of my invention selected for purposes of illustration and shown in the drawings, I provide, as shown particularly in Figs. 1 and 2, a window frame 1 having an outer casing provided

with grooves 3 formed along opposite adjacent sides thereof for receiving suitable guiding strips 4. The strips 4 are desirably formed of relatively thin, stiff metal doubled lengthwise to form a folded edge 5 which

protrude from the grooves 3. The edges 5 of these strips which are formed by folding the same longitudinally, as hereinbefore stated, when pressed closely together are inserted in the slots 3, and along opposed faces

of said strips, which are inserted as aforesaid, the metal composing the said strip is provided with spurs 6 which extend outwardly from said opposite faces, and when these strips are forced into the slots the said spurs

effect a gripping action to prevent said strips from being too easily withdrawn from the slots, sufficient resiliency being inherent in the folded metal strips to provide a spreading action upon the two parts 7 and 8 of the folds thereof to cause said metal strip to retain its hold and position in said slot.

Slidably arranged upon the guide members or strips 4 is a screen 9 of any suitable construction and having formed in one edge, herein the edge 10, a groove of sufficient depth

to receive a large portion of the protruding portion of the folded edge 5 and slide freely upon said strip.

The opposite edge or side of the screen is rabbeded at 11 to cooperate with the slot or groove 13 in permitting the screen to be inserted or removed from the frame or from the guiding strips in said frame, said screen frame being also provided with a recess 12 to align with the groove 13 at the opposite edge of the screen.

Arranged at a plurality of points along the groove 13 of the first-mentioned edge are helical springs 14 which are inserted at said plurality of points in holes 15 formed in said edge and wherein said spring are secured, herein by small brads or similar means 15' which are driven into the side of said screen, for example between the adjacent inner coils of said spring. The outer ends of said springs 14 are arranged to cooperate with the folded edge 5 of the adjacent guide strip so as to exert pressure upon said screen toward the opposite or removable side of the window.

Effectively to guide the springs 14 along the folded edge 5 of the strips 4, I preferably provide a collar 16 which has a transverse depression 17 in its outer edge to receive said folded edge 5 and serve as a guide to retain said screen in proper sliding position. The rim of the collar 16 is flanged at 18 and in any suitable manner is secured to the outer coils of the spring 14, as for example by being screwed upon said flange in grooves 19. The collar 16 and spring 14 are loosely fitted within the recesses 12 in the edge of the screen and completely close said recesses to prevent mosquitoes, flies and the like from working into the recesses provided for said spring 14 around the edge 5 of the guide member 4. The opposite edge of the screen is also provided with a groove 20 to receive the folded edge 5 of the guide member 4 for that other side of the screen and guide said screen during its sliding movements in the frame 1.

To provide a freer relative movement between the screen and guide strip 4 I provide grooved rollers 21 pivoted at 22 within the groove 20, the grooves in said rollers being adapted to insure the traveling of the screen edge

upon said guide strips 4. Cooperating with said rollers 21 I also provide a rotatable element 23, herein pivotally secured by the screw 22 within the rabbet 11 and concentric with the roller 21. The rotatable element 23 has one side flattened off or otherwise reduced in diameter at 24, and this rotatable element is so arranged within the rabbet 11 that when it is turned 10 with the flattened face inward, as shown in Figs. 1 and 2, the outer periphery of said rotatable element will project approximately evenly with the outer edge 25 of said screen, but upon rotating said rotatable member 15 about 180 degrees the flattened side 24 will be brought to a position aligning with the inner edge of the guide strip 4 and permit the screen to be removed from engagement with said guide member and said roller 21, after 20 pressing said screen toward the left slightly to compress the spring 14 sufficiently to release the folded edge 5 from engagement with the groove of said roller 21. The screws 5 for securing the rotatable member in the rabbeted portion of said screen may also be used 25 to prevent said rotatable member from rotating during the sliding operations of the screen, this being effected by the tightening of the screw in the screen frame.

30 In Figs. 3 and 4 I have shown a slightly modified construction in which the window screen is shown as a full length screen 26 and is therefore incapable of sliding movement in the window frame 27. In this form it is 35 not necessary to provide yielding means in one side of the screen, as shown at the left of Fig. 2, because said screen may be swung into place about a strip 28 which extends herein across the top of the window frame and is 40 arranged to fit into a groove 29 and hinge about the strip 28. Both sides of the screen 26 are, however, rabbeted as shown at 30 and when the screen is swung into place about the pivoting strip 28 the rabbeted portions of 45 said screen are adapted to seat against the guide strips 31 and 32 at opposite sides respectively of the window frame, and after said screen has been swung into place means may be employed for locking the same in their rabbeted engaging position. For example, in this 50 connection rotatable elements 33 similar to the rotatable elements 23 of the form shown in Fig. 2 may be used, two of which may be shown near the lower ends of the screen and others, for example near the center thereof, as 55 shown at 34, although it is to be understood that the number and location of these rotatable elements may be varied to suit the occasion, and when these screens are to be removed these rotatable elements may be turned until the flattened parts 35 are aligned with the inner edges of the guide strips 31.

60 The construction herein described provides a strong and effective guide strip of very little thickness, requiring only a very narrow

groove in the edges of the screen and thereby rendering the screen stronger and much less liable to result in the breaking away of one or the other side of the screen, and furthermore all holes will be effectively closed to insects by reason of the narrow grooves in the sides of the screen and the addition of the caps 16 which engage the folded edges of said guide strips, and at the same time completely close the openings through the centers of the springs 14. Furthermore, the guide strips being of metal may be projected a greater distance beyond the inner edges of the window frames and provide greater distances between the edges of the screens and the edges of the window frames, whereby variations in the sizes of the screens due to warping or shrinking or expanding thereof will not cause any unnecessary binding of the screens in the window frames. Another advantage of the present construction is in the great saving in labor produced by this construction, whereby the grooves 3 formed in the window casings may be produced quickly, for example by means of a motor driven saw which may be quickly moved along the inner edges of said window frames to cut said grooves and the guiding strips may then be readily inserted in the grooves without nailing and remain in said grooves indefinitely. It is also to be understood that it is within the scope of the invention to form the guiding strips upon the screen and the cooperating guiding elements in the window frame.

65 The invention is not limited to the specific embodiment shown.

Claims:

1. In combination, a window casing having grooves formed in the edges thereof, a guide strip formed of metal and folded longitudinally, said strip being inserted in said groove with the folded edge of said strip protruding from said groove, and spurs formed in said strip adapted to retain said guide strip within said groove.
2. In combination, a guide strip for a window screen, a grooved side member to slide upon said guide strip, helical springs inserted in an edge of said screen, and a collar secured to the outer end of each of said springs and provided with a transverse groove slidably to engage the edge of its guide strip and to close the opening through said spring.
3. In combination, a window screen having a guiding groove in one edge, helical springs arranged at spaced intervals in said grooved edge, transversely grooved caps for the outer ends of said springs, said grooves arranged to align with said groove and close the openings through said springs, and means detachably to secure said screen at its opposite edge.
4. The combination, with an outside window casing having saw cut grooves formed longitudinally of the inner edges thereof, of a guide strip formed of longitudinally folded

sheet material inserted in each of said grooves with its folded edge protruding from said groove, and means to secure its guide strips in said grooves.

5. The combination, with an outside window casing having narrow grooves formed longitudinally of the inner adjacent edges thereof, of guide strips formed of longitudinally folded sheet metal inserted in said grooves with the folded edges protruding and forming screen guides, and means dependent upon the natural resiliency of said folded sheet metal to retain said guide strips in said grooves.

10 15 In testimony whereof, I have signed my name to this specification.

JOSEPH E. JOHNSON.

CERTIFICATE OF CORRECTION.

Patent No. 1,824,897.

Granted September 29, 1931, to

JOSEPH E. JOHNSON.

It is hereby certified that error appears in the printed specification of the above numbered patent requiring correction as follows: Page 1, line 66, for "spring" read springs; line 85, for "losely" read loosely; page 2, lines 103 and 104, claim 1, for "havin" read having"; page 3, line 2, claim 4, for "said" read its, and line 3, for "its" read said; and that the said Letters Patent should be read with these corrections therein that the same may conform to the record of the case in the Patent Office.

Signed and sealed this 17th day of November, A. D. 1931.

(Seal)

M. J. Moore,
Acting Commissioner of Patents.
